(57) **CLAIM**

The ornamental design for a washer for cutting tools, as shown and described.

DESCRIPTION

FIG. 1 is a top perspective view of a washer for cutting tools showing an embodiment of our new design;
FIG. 2 is a bottom perspective view thereof;
FIG. 3 is a top view thereof;
FIG. 4 is a bottom view thereof;
FIG. 5 is a front view thereof, with left side, right side, and rear views being identical to the front view;
FIG. 6 is a top perspective view of a washer for cutting tools showing a further embodiment of our new design;
FIG. 7 is a bottom perspective view thereof;
FIG. 8 is a top view thereof;
FIG. 9 is a bottom view thereof; and,
FIG. 10 is a front view thereof, with left side, right side, and rear views being identical to the front view.
The washer for cutting tools of FIGS. 1-5 is rotationally symmetrical around a central axis thereof.
The washer for cutting tools of FIGS. 6-10 is rotationally symmetrical around a central axis thereof.
The broken lines show portions of the washer for cutting tools that form no part of the claimed design.
